WHEEL POLISHING MACHINE

Frank L. Armitage, Fall River, and Edwin N. Broden, Assonet, Mass., assignors to The Firestone Tire & Rubber Company, Akron, Ohio, a corporation of Ohio

Application January 9, 1947, Serial No. 720,964

2 Claims. (Cl. 51—74)

1

This invention relates to wheel-polishing machines, and more especially it relates to apparatus for polishing small wheels or casters made of molded, heat-hardened plastic such as hard rubber or rubber-like composition.

Wheels of the character mentioned usually are shaped and vulcanized in a cavity in a suitable separable mold structure that leaves an overflow fin or rind circumferentially of the wheels in the central plane thereof. Subsequently the wheels are subjected to a finishing operation which consists of removing the overflow rinds and then smoothing the perimeters of the wheels by buffing the same. The final operation on the wheels is the polishing thereof which is effected on the perimeter and the lateral faces of the wheels. Prior to the present invention such polishing was achieved by lengthy tumbling of the wheels to obtain the desired finish thereon.

The chief objects of the invention are to provide in an improved manner for polishing articles of the character mentioned; to obtain a product having superior finish; to reduce the amount of handling of the articles; and to reduce the cost thereof. Other objects will be manifest as the description proceeds.

Of the accompanying drawings:

Fig. 1 is a side elevation of apparatus embodying the invention;

Fig. 2 is an end elevation thereof as viewed from the left of Fig. 1; and

Fig. 3 is a plan view of the apparatus.

Referring to Figs. 1 and 2 of the drawings, it will be seen that the machine comprises a centrally positioned base casting 10 that supports a shelf 11, and rising from opposite lateral marginal portions of the latter are superposed channels 12, 12 that support a table-like structure 13. Rising from the latter at spaced points longitudinally thereof are pairs of posts 14, 14, Fig. 2, each pair of which carries at the top thereof a small shelf 15 upon which is fixedly mounted an upright angular arm 16. The latter has one side thereof of concave shape formed by the juncture of two outwardly diverging faces, and in said concavity is located an elongate tubular work-holding structure 17. The structure 17 is retained in engagement with each arm 16 by a stirrup clamp 18 that straddles the arm and embraces said structure, said clamp comprising a manually operable threaded member 19 that engages the arm on the side thereof opposite said concavity, for tightening the clamp about the tubular structure 17. The arrangement is such that work-holding structures 17 of different diameter than that shown easily and readily may be mounted for use in the machine. As is best shown in Fig. 3, the work-holder 17 is cut away at 20, 20 at diametrically opposite portions thereof and at two adjacent, but longitudinally spaced

regions, whereby a plurality of work-units within the holder are exposed so that work may be performed upon them. Said work units consist of annular discs 21 of heat-hardened plastic material, such as rubber or rubber-like composition.

The work-holder 17 extends to one end of the table 13 (the left) as viewed in Fig. 1 and extends beyond said table at the opposite end thereof, where it extends through a substantially closed cabinet 24. Within this cabinet the work-pieces 21 are subjected to an abrading operation that transversely flattens their respective peripheral surfaces, that is, removes the overflow rind and the crown that are present on the discs as they come from the mold. To this end a hollow base structure 25 is mounted in the lower part of the cabinet 24, and mounted atop of said base structure are spaced apart tube-supporting structures 26, 26, which structures are similar to the structures comprising elements 14, 15, 16, 18 and 19 previously described. The work-holder 17 extends through the end-wall of the cabinet 24, at the right thereof as viewed in Fig. 1, and is open so that an operator stationed thereat may manually insert work-pieces 21 into the open end of the work-holder and urge them toward the opposite end thereof. The work-holder 17 is recessed or cut away at diametrically opposite sides of a local region thereof, as indicated by the broken lines 27 in Fig. 1, to expose the work-pieces 21 in the holder, so that work may be performed thereon. To this end an endless driven belt 28 having an operative surface treated with emery or sand is provided, said belt being arranged to operate upon the perimeters of successive work-pieces 21 as the latter are exposed through one of the openings 27 in the work-holder during their progress therethrough. As the work-pieces are abraded by the belt 28 they are rotated by a suitable rotary member (not shown) that engages them through the other opening 27 in the work-holder 17. Said rotary member is carried in a frame structure 29 that is mounted upon the base 25 and is adjustable from and toward the work-holder by means of a hand-wheel 30. The aforesaid rotary member includes a shaft 31 that carries a pulley 32 about which is trained a transmission belt 33, the latter also having driving connection with a motor (not shown) located within the base structure 25. The apparatus located within the cabinet 24 is not a part of the present invention, and for this reason it is believed that a more comprehensive description will not be necessary.

As previously stated, work is performed upon the work-units 21 in the work-holder 17 in those regions where the work-units are exposed to view through the cut away portions 20 of said holder. Through the opposed openings 20 nearest the cabinet 24 the work units are operated upon by an

endless friction-faced propulsion belt 35 and a rotary buff 36 composed of soft bristles, said belt and buff being in opposition to each other on opposite side of the work-holder 17 and engaging the work through respective openings 20. The function of the belt 35 is to rotate the work-units 21 with which it is engaged, the direction of rotation of said work-units being such that the regions thereof in engagement with the buff 36 move counter to the rotation of the buff. The buff 36 is mounted upon one end of a shaft 37 that is journaled in the free end of a swingable bearing arm 38, the other end of the latter being journaled in suitable bearing brackets 39 mounted atop of table 13. A fixture 40 mounted upon the top of table 13 carries a manually turnable adjusting screw 41 that has threaded engagement with the arm 38, the arrangement being such that the buff 36 may be adjusted from or toward the work 21, as desired. The buff 36 is covered by a suitable guard 42 except at the region thereof where the buff engages the work. For rotating the buff 36, the end of shaft 37 remote from the buff carries a pair of pulleys 43, 43 about which are trained respective transmission belts 44, the latter also being trained about respective pulleys 45 that are mounted upon an elongated countershaft 46 that is journaled in the bearing brackets 39 aforementioned. The pulleys 43, 45 and belts 44 are enclosed in a suitable guard 47. The extremity of the countershaft 46, at the right thereof as viewed in Figs. 1 and 3, carries a pair of pulleys 48, 48 about which are trained respective transmission belts 49, the latter also being trained about respective pulleys 50 that are mounted upon the shaft 51 of a motor 52, the latter being mounted upon the shelf 11. A manually operable switch 53 is provided for controlling the operation of the latter.

Mechanism for operating upon the work-units 21 through the aligned apertures 20 remote from the cabinet 24, which is to the left of the apertures 20 previously mentioned, as viewed in Fig. 3, is essentially similar to the mechanism described in the preceding paragraph. Thus the work is exposed to the action of a rotary endless friction-faced propulsion belt 55, and a buff or brush 56 composed of soft bristles. The latter is mounted upon one end of a shaft 57 that is journaled in the free end of a swingable bearing arm 58, the other end of which is journaled in bearing brackets 39 upon the top of table 13, said bearing brackets being identical with the bearing brackets 39 previously mentioned, and serving with the latter as journals for the countershaft 46. A manually rotatable adjusting screw 59 is mounted in a fixture 60 on top of table 13 and is threaded through arm 58 for swinging the latter to move the buff 56 from and toward the work. The usual guard 61 covers the buff 56 except at the region thereof where it engages the work. For rotating the buff 56, the end of shaft 57 remote from the buff carries a pulley 62 about which is trained a transmission belt 63 that also is trained about a pulley 64 mounted upon the adjacent end portion of countershaft 46. A guard 65 encloses pulleys 62, 64 and belt 63. The arrangement is such that the buffs 36, 56 may be urged against the work with different pressures.

The endless propulsion belts 35, 55 are similarly mounted, and are driven at the same surface speed by a shaft 66 that is common to both of them. Said shaft is journaled at its opposite end portions in bearing brackets 69, 70 that are

mounted upon the top of table 13, rearwardly of the work-holding structure 17. The end of shaft 68 adjacent bracket 70 is provided with a pulley 71 about which is trained a transmission belt 72, which belt also is trained about a pulley 73 mounted upon an elongate countershaft 74 that is journaled in bearing brackets 75, 75 rising from the channel members 12 at the rear of the machine. One end of countershaft 74 is provided with a pulley 76 about which is trained a transmission belt 77, the latter also being trained about a pulley 78 that is mounted upon the shaft 51 of motor 52.

The propulsion belts 35, 55 are each mounted upon a pair of pulleys, the lower pulley 80 of each pair being mounted upon and driven by the shaft 68, as shown in broken lines in Fig. 2. The upper pulley of each pair, of which one is shown in Fig. 2 and designated 81, is rotatably mounted in the upper, free ends of a pair of swingable arms 82, 82, which arms are pivotally mounted at their lower ends upon the shaft 68. Each arm 82 is connected, intermediate its ends, to its companion arm 82 by a rearwardly extending yoke 83, and the latter are connected to respective manually operated adjusting screws 84 that are threaded through respective upstanding fixtures 85 that are mounted upon table 13. The arrangement is such that the propulsion belts 35, 55 are independently adjustable from and toward the work.

The function of the buffs 36, 56 is to distribute polishing compound about the perimeters of the work-units 21 and to polish the latter, the action of the two buffs being identical and the results being cumulative. Polishing compound is applied to the work-units through a circular aperture in the top of work-holder 17, said aperture being indicated by dotted lines 88, Fig. 3, and being located in the work-holder between the cabinet 24 and the nearest opening 20 in the work-holder. The polishing compound is applied to the work-pieces in the form of a spray, and to this end a spray gun 89 is located above said aperture 88 in position to discharge thereunto. The polishing compound is a fluent substance comprising a wax base, and a black dye adapted to cover up blemishes on the work-pieces. The polishing liquid reaches the spray gun by means of a conduit 90 that has connection with a reservoir of the liquid under pressure (not shown). The polishing liquid is discharged from the spray gun intermittently by means of air under pressure that reaches the spray gun by way of a conduit 91. In the latter are the usual regulating valves 92 and pressure gauge 93, and a shut-off valve 94 that is located adjacent the end of shaft 68 remote from pulley 71, said conduit extending to a source of air under pressure (not shown). A cam 95 is mounted upon the end of shaft 68 and adapted operatively to engage valve 94 with each revolution of shaft 68 and thus momentarily and periodically to arrest the passage of air through conduit 91 to the spray gun 89. Air discharging from the spray gun sprays polishing liquid upon the work-units 21. By reason of its intermittent operation, the spray gun is kept open and clean at all times. The air-off condition of the spray gun is of such short duration that no work-units may pass the same without being sprayed with polish.

After being peripherally polished, the work units 21 are ejected from the work-holder 17 at the left end thereof as viewed in Figs. 1 and 3. Mounted upon the top of said holder 17 and pro-

jecting beyond the delivery end thereof is a leaf spring 98 adapted to bear upon the tops of the successive work-units 21 as they issue from said work-holder and thus to force the said units downwardly while disposed in a vertical plane. The falling work units are received in an inclined chute 99, the upper end portion of which is located at the delivery end of holder 17. The lower end of chute 99 is open, and located at one end of a work-guiding structure comprising a pair of horizontally disposed, parallel, channels 100, 100, the gutters of which are in confronting relation. The channels 100 extend transversely of the work-holder 17, one channel being located above the other. The lower channel 100 is fixedly positioned. The upper channel 100 is carried by a pair of supporting members 101, 101, each of which includes a compression spring 102, the arrangement being such that the upper channel is yieldingly urged downwardly toward the lower channel. Work-units 21 are received between the channels 100 and lightly peripherally engaged thereby as they move longitudinally of the channelled structure, a polishing operation being performed on the exposed lateral faces of the work-units as they traverse the work-guiding structure.

Work-units falling down the chute 99 land in a vertical plane at one end of the guide structure comprising the channels 100, and power operated means is provided for impelling a file of the work-units longitudinally of the guide structure in a step-by-step movement. To this end a suitably shaped reciprocable head 104 is mounted on the table 13 adjacent the work-receiving end of said guide structure, the end of the head remote from the latter being connected to one end of a slidably mounted push rod 105. The other end of the latter is pivotally connected at 106 to one end of a pitman 107, the other end of said pitman being pivotally connected to a rotary disc 108 eccentrically of the axis thereof. The disc 108 is mounted upon the end of countershaft 74, remote from the pulley 76 thereon. The countershaft 74 rotates constantly while the machine is in operation, thus effecting reciprocation of head 104 to move work-pieces 21 in succession through the guide structure composed of the channels 100.

As the work-units 21 traverse the said guide structure their exposed lateral faces are polished by respective rotary buffs 110, 111 that are disposed on opposite sides of the guide structure and rotate in opposite directions. Said buffs are journaled in respective sub-frame structures 112, 113, which structures also carry respective motors 114, 115. The latter have driving connection with the buffs 110, 111 through the agency of respective transmission belts 116, 117. The sub-frames 112, 113 are adjustably mounted upon a supplementary frame 118 that is offset from the main frame of the machine at one end thereof, the arrangement being such that each buff and its companion motor may be moved relatively of the work-units in the guide structure to compensate for wear on the buffs. A manually operated switch 119 is provided for controlling the operation of the motors 114, 115.

It will be apparent that both lateral faces of the work-units 21 are polished as said work-units progress step by step through the work-guide structure. The finished work-units fall from the open outer end of the latter and are received in any suitable receptacle thereat (not shown).

The invention provides a relatively simple ap-

paratus for performing operations of the character described, and said apparatus readily may be altered and adjusted to accommodate work-units of different sizes. The invention effects a saving of labor as compared to prior practise, and achieves the other advantages set out in the foregoing statement of objects.

Modification may be resorted to without departing from the spirit of the invention, or the scope thereof as defined by the appended claims.

What is claimed is:

1. In a polishing machine of the character described, the combination of a work guide adapted to support a succession of wheels by engagement with the perimeter thereof, said work guide comprising a pair of parallel, spaced apart channel members with the channels thereof in confronting relation, one of said channels being fixedly positioned, the other channel being lightly urged toward said fixedly positioned channel, said wheels disposed in the same plane in peripherally abutting relation, polishing means on opposite sides of the work guide adapted to operate on the opposite lateral faces of the wheel, and means for moving the wheels through the work guide.

2. In a polishing machine of the character described, the combination of an elongate, tubular work-holder through which a succession of small loading wheels in lateral contact with each other move in an axial direction, said work-holder being locally apertured on diametrically opposite sides thereof into exposed peripheral regions of the work therein, an endless propulsion belt, driven by a shaft, peripherally engaging work-pieces through one of said apertures to rotate said work-pieces, and a rotary buff peripherally engaging the work-pieces through the other aperture to polish the peripheral regions of said work-pieces, said work-holder having an aperture through its wall for the entrance of a polishing fluid therein, means for intermittently injecting said polishing fluid into the work-holder, said means comprising a spray gun connected by a conduit with a source of said polish under air pressure, a shut-off valve in said conduit, cam means mounted on said shaft adapted to contact and close said valve at each rotation of said shaft.
